CLAIM

The ornamental design for a tummy control shorts, as shown and described.

DESCRIPTION

FIG. 1 is a perspective view of a tummy control shorts design showing our new design.

FIG. 2 is a front view thereof.

FIG. 3 is a rear view thereof.

FIG. 4 is a left side view thereof.

FIG. 5 is a right side view thereof; and,

FIG. 6 is a rear, left perspective view thereof.

The broken lines representing stitching are part of the claimed design.

The various styles of surface shading applied to the surface of the tummy control shorts represent a contrast in appearance and form no part of the claimed design.

1 Claim, 6 Drawing Sheets
